UNITED STATES PATENT OFFICE.

LOUIS MAURICE BARMAN, OF LONDON, ENGLAND.

APPARATUS FOR PRINTING ADDRESSES OR OTHER MATTER ON ENVELOPES, LABELS, OR THE LIKE.

Application filed July 9, 1923. Serial No. 650,346.

To all whom it may concern:

Be it known that I, LOUIS MAURICE BARMAN, a citizen of the United States of America, residing at Roneo Building, 5 Holborn, London, E. C. 1, England, Great Britain, have invented new and useful Improvements in Apparatus for Printing Addresses or Other Matter on Envelopes, Labels, or the like, of which the following is a specification.

The present invention relates to apparatus for printing addresses or other matter on envelopes, labels or the like.

Machines for this purpose, are mostly of complicated design in that it has been the aim to accomplish the various movements as far as possible by automatic means. For this and other reasons, therefore the cost of a machine for addressing envelopes or printing other matter from stencil cards is sufficient to prevent a man in a small way of business acquiring apparatus of this nature.

Now the object of the present invention is to construct, in as simple a manner as is practicable, apparatus for printing addresses on envelopes, or other matter from stencil cards, so that such can be sold at approximately one quarter of the price at which existing so called automatic addressing machines are retailed.

The present invention consists in apparatus for printing addresses or other matter on envelopes, labels, or the like comprising in combination a box or case fitted with a drawer for storing the stencil cards, a track or slideway secured to the top of the box, a hopper or magazine also secured to the box, a hand operated slide movable in the slideway for acting on the lowermost stencil card, an adjustable gauge for envelopes secured to said box or case, and a receptacle at one side of the box or case which has secured therein the major portion of the means for effecting the printing from the stencil cards.

The invention also has for its object certain improvements in mounting and control of the inking rollers.

The construction and operation of the apparatus will be easily understood from the following description, reference being had to the drawings whereon:—

Fig. 1. is a plan view of the apparatus.

Fig. 2. is a front view.

Fig. 3. is a detail view of the action of the inking mechanism.

Fig. 4. is a side view of the receptacle showing the mounting therein of the inking device.

According to the invention, the box or case 1 is preferably constructed of wood. The front of the box is provided with a drawer 2 of a size sufficient to store say one hundred stencil cards 3. To the top of the case is secured by screws 4 or like means 65 a thin metal plate formed with channelled edges which constitute a slideway or track 5 for the stencil cards 3.

At one end of the track 5 and secured to the top of the box by screws or like means 70 are two uprights preferably formed from metal having short flanged edges bent inwardly and projecting over the channels formed on the track, the said uprights forming the hopper or magazine 6 for the stencil 75 cards. The base of one of the uprights is extended and is flanged over as at 7 to form a housing or bearing for a lever 8 one end of which is secured to a metal slide 9 which fits in the slideway or track, so the other end of the lever being formed into a finger and thumb piece 8^a for reciprocating the slide 9 in the slideway or track.

At a point near the other end of the fixed track or slideway 5, a slot 10 is made 85 in the track as well as in the top of the box or case, and the side of the box at this end of the apparatus is provided with a door or flap 11 so that a compartment 12 is formed between the drawer 2 and one side 90 of the box. Secured to the underside of the top of the box, in the compartment 12 thus formed, as by bolts, screws or the like 13 is a casting 14 which has a lug or bracket 14^a which projects upwardly through a slot 15 95 formed in the top of the case, the said slot being in alignment with the slot 10 in the slideway 5. The lug or bracket 14^a is bored out to receive a shaft 16 to one end of which is secured an operating handle 17, the other 100 end having affixed thereto a segmented presser roller 18, the portion of the shaft 16 between the lug or bracket 14^a and the segmented roller 18 being preferably enclosed in a sleeve 19 secured to a lug 14^b. Between 105 the operating handle 17 and the lug or

bracket 14^a, there is mounted on said shaft 16 a gear wheel 20 which gears with a further wheel 21 mounted on a shaft 22 supported in bearings in the casting 14.

5 The other end of shaft 22 has secured to it a segmented inking roller 23 which projects through slot 10 and makes contact, at will with a metal inking roller 24 carried in arms 25 pivoted at 26 to lugs 14^b formed on 10 the casting 14.

On the pivot 26 are mounted a pair of arms 27 between which is freely mounted a felt roller 28 which can be inked by hand.

15 The metal roller 24 is kept in normal contact with the segmented inking roller 23 by means of a spring or springs 29, and in a similar manner constant contact is ensured between the metal roller 24 and the felt roller 28 by springs such as 30.

20 The spindle of the metal roller 24 is projected through its bearing and a hole is formed in the rear wall of the box 1 so that a handle 31 can be passed over the end of the spindle. By turning the handle 31 the metal roller 24 is rotated and collects ink 25 from the felt roller 28.

The arms 25 carrying the metal roller are 30 provided with spurs or projections 32 and the lugs 14^b of casting 14 are bored out to receive a rod 33, which can be turned by hand. The said rod has a flattened surface 33^a formed on it and is normally in frictional contact with the spurs or projections 32. The arrangement is such that when the flattened surface 33^a of rod 33 is turned towards the spurs or projections 32 no pressure is exerted against them and the spring or 35 springs 29 pull the metal roller 24 into engagement with the segmented inking roller 23 (see dotted lines Fig. 2).

40 When however the rod 33 is turned so that the rounded part presses on the spurs 32 the arms 25 carrying the metal roller 24 are depressed, and contact between the segmented inking roller 23 and the metal roller 24 is interrupted (see Fig. 3). This depression of the arms 25 is also transmitted to the felt roller 28, but by reason of the spring or 45 springs 30 contact between the two rollers 24 and 28 is always maintained.

The inking arrangement above described, is a modified form of the apparatus described, illustrated and claimed in United States Patent No. 1,411,398.

50 Secured to the top of the box or case 1 is a gauge 34 for the envelopes, labels, or the like which is adjustable across the track or slideway 5, the said gauge comprising a U shaped rod 34^a pivoted in brackets 34^b secured to the top of the box, the free ends 55 of the rods having adjustably attached thereon a floating bar 34^c which is lifted by each stencil card 3 and rests thereon as each card 60 is pushed by the slide 9 to its printing position between the segmented rollers 18 and 23

and against the front edge of the bar 34^c the forward edge of each envelope, label or the like is pushed.

The apparatus is worked as follows:—

A batch of stencil cards 3 are taken from 70 the drawer 2 and are dropped into the hopper or magazine 6. The flap or lid 11 is let down, and ink is applied from a tube, bottle or the like to the felt roller 28. The small handle 31 fitting over the metal roller 75 shaft is now turned so that the ink is distributed over the surface of the metal roller 24, and the said metal roller is afforded contact with the segmented inking roller 23 by turning the rod to the position shown 80 in dotted lines Fig. 3.

The reciprocating slide 9 is now moved by the lever 8 so that the lowermost stencil card in the hopper or magazine 6 is pushed to a position approximately as shown in Fig. 1. 85

A second movement of the slide 9 is now necessary so that the second card withdrawn on the forward movement of the slide pushes the first card to its printing position underneath the floating bar 34^c of the gauge 34 90 and between the parted segmented presser roller 18 and inking roller 23.

At this stage an envelope, label or the like is placed by hand over the slideway 5 with the stencil card 3 therein, so that the foremost edge of the envelope registers against the floating bar 34^c of the gauge 34. 95

The operating handle 17 is now turned which causes the segmented presser roller 18 and inking roller 23 to grip and move the 100 envelope and stencil card 3, and the ink from the roller 23 is forced through the perforations of the stencil onto the envelope or label in the well known manner.

When the rollers 18 and 23 part, the slide 105 9 is again reciprocated and the second stencil card is positioned by the withdrawal of the third.

A second envelope is placed over the said card and movement of the handle 17 causes 110 the second card to push the first card out of the slideway 5 so that it drops down on to the lowered flap or lid 11.

When all the cards are used they are returned by hand to the drawer 2 and a second 115 batch is used.

Modifications of the apparatus may be made to suit special conditions, and the position of the drawer 2 and the flap or door 11 of the compartment 12 may be altered. 120

Moreover, the handle 17 and the handle 31 for causing ink distribution may be removably fitted to their respective shafts.

Having thus described my invention, what I desire to secure by Letters Patent of the 125 United States is as follows:—

In a stencil printing apparatus, a casing, a trackway on said casing, a stencil magazine at one end of said trackway, a slide movable in said trackway for feeding stencils 130

from said magazine along said trackway, an extension on said magazine, a lever mounted in said extension and connected to said slide for operating the same, a gauge adjacent said trackway for maintaining an envelope in cooperative relation to a stencil in said trackway, a printing mechanism enclosed within said casing and to which said stencil is fed,

rotatable means operable independently of said lever for actuating said printing mechanism, and a closure for one end of said casing movable to an open position to receive the stencil after the printing operation. 10

In testimony whereof I have signed my name to this specification.

LOUIS MAURICE BARMAN.
